UNITED STATES PATENT OFFICE

158,880

POWER UNIT

Jack Morgan, Chicago, Ill., assignor to Dormeyer Corporation, Chicago, Ill., a corporation of Illinois

Application July 5, 1947, Serial No. 140,117

Term of patent 7 years

(Cl. D44—1)

To all whom it may concern:

Be it known that I, Jack Morgan, a citizen of the United States, residing at 180 East Delaware Place, in the city of Chicago, county of Cook, and State of Illinois, have invented a new, original, and ornamental Design for a Power Unit, of which the following is a specification, reference being had to the accompanying drawing, forming a part thereof:

Fig. 1 is a top plan view of a power unit showing my new design;

Fig. 2 is a side elevational view thereof;

Fig. 3 is a rear elevational view thereof; and
Fig. 4 is a front elevational view thereof.

I claim:

The ornamental design for a power unit, as shown.

JACK MORGAN.
